UNITED STATES PATENT OFFICE

150,894

DESIGN FOR A FOLDING ROCKING CHAIR OR SIMILAR ARTICLE

Herman A. Smith, New York, N. Y.

Application March 21, 1947, Serial No. 137,794

Term of patent 7 years

(Cl. D15—6)

To all whom it may concern:

Be it known that I, Herman A. Smith, a citizen of United States, residing at New York city, in the county of New York and State of New York, have invented a new, original, and ornamental Design for Folding Rocking Chair or Similar Article, of which the following is a specification, reference being had to the accompanying drawing, forming part thereof.

In the drawing the single figure of the drawing is a perspective view of a folding rocking chair embodying the invention.

I claim:

The ornamental design for a folding rocking chair or similar article, as shown.

HERMAN A. SMITH.
